UNITED STATES PATENT OFFICE.

THEODORE W. FOSTER, OF PROVIDENCE, RHODE ISLAND.

DESIGN FOR A HANDLE FOR MANICURE OR SIMILAR ARTICLES.

SPECIFICATION forming part of Design No. 28,528, dated May 3, 1898.

Application filed March 31, 1898. Serial No. 676,004. Term of patent 7 years.

To all whom it may concern:

Be it known that I, THEODORE W. FOSTER, of Providence, in the county of Providence and State of Rhode Island, have invented and 5 produced a new and original Design for the Handles of Manicure and Similar Articles, of which the following is a specification, reference being had to the accompanying drawing, forming part thereof.

10 The drawing is a side view of the handle, showing my design. A nail file and scraper are indicated in broken lines secured to the handle.

15 The leading and material feature of my design consists in the series of raised foliations extending each from a scrolled stem along the margin of the handle, as will be more fully set forth hereinafter.

20 In the drawing, 2 indicates the beaded end of the handle. A row of graduated semi-spherical beads 3 extend from the beaded end along the center of the handle, and on each side along the margin of the handle extend the obliquely-disposed foliations 4, from the

25 ends of which the foliated scrolls 5 follow the outline of the handle, united by the transversely-extended scroll 6, from which a graduated string of beads extends along the center. The foliated scrolls 7 extend along the edges 30 of the handle, curving inward at their ends, and connect with the foliated scrolls 8, which extend from the ornament 9 at the end of the handle. The foliated scrolls 5, 7, and 8 inclose plain surfaces on the central portion of the handle. All the ornamental scrolls and 35 beads are in relief.

Having thus described my invention, what I claim as new, and desire to secure by Letters Patent, is—

The design for the handle of manicure and 40 similar articles herein shown and described.

In witness whereof I have hereunto set my hand.

THEODORE W. FOSTER.
